DESIGN FOR A PORTABLE ELECTRIC POLISHING UNIT OR THE LIKE

George D. Behlen, Cincinnati, Ohio

Application November 16, 1940, Serial No. 96,641

Term of patent 14 years

To all whom it may concern:

Be it known that I, George D. Behlen, a citizen of the United States, residing at Cincinnati, in the county of Hamilton and State of Ohio, have invented a new, original, and ornamental Design for a Portable Electric Polishing Unit or the like, of which the following is a specification, reference being had to the accompanying drawing, forming a part thereof, in which:

Fig. 1 is a side elevational view of a portable

electric polishing unit or the like showing my new design;

Fig. 2 is a plan view of the same portable electric polishing unit or the like; and

Fig. 3 is a front view of the same portable electric polishing unit or the like.

I claim:

The ornamental design for a portable electric polishing unit or the like, substantially as shown.

GEORGE D. BEHLEN.
